(76) Inventors: **John Cole; Samuel Miller**

*John Cole of Washington County Ohio
Assignee of Samuel Miller
Sellers Patent.*

The Schedule referred to in this Sellers Patent and making part of the same containing a description in the words of the said Schedule, namely of Samuel Miller themselves of their improvement in the machine for the manufacture of Barrels, Yards and other Cooper's ware.

To all to whom these presents shall come. Be it known that we John Cole of the County of Washington State of Ohio, and Samuel Miller of the Town and County of Athens, in the State aforesaid have made an improvement, being a machine for making Barrels, Yards, Drums and other Cooper's ware which is described as follows.

This machine consists of the following parts. 1st The frame. 2nd The part to shave Staves. 3rd The part to shave heads. 4th The part to joint Staves. 5th to turn and draw the heads. 6th The part for drawing the barrel and cutting the ends. 7th part for facing the heads. 8th Cog wheels of shaft drum and others.

1st The frame is made by splicing together two long timber, 6 pieces and four end pieces, having iron cross pieces placed at proper distances apart between the long timber the which forming a frame about 14 feet long, three feet more or less wide and about four feet high properly braced on the sides. 2nd The part to shave Staves. It will consist of the frame mentioned and across it are placed two pieces of scantling being about five feet long and of suitable breadth and thickness placed about 8 inches apart. Between these pieces are placed iron rollers with their quidgous turning in their middle pieces. Near the centre of the frame is placed a roller having small iron points on its periphery, called a burned roller, its sides projecting beyond the side pieces and on its end a small cog wheel meshing into a large one on the main shaft below hereafter to be described. This burned roller is for facing forward the staves to be shaved, over the burned roller is placed another roller, thicker in the middle than at its ends, with its quidgous turning

in slides, let into pieces, and operated by springs secured to top of side pieces. This roller with its slides and springs rises and falls to suit the thickness of the slave as it passes between it and the barred roller. The knives should be irregular in thickness, in front of the barred roller is placed a smaller roller to assist in guiding the slaves to the knives. The knives are placed over this small roller with their front edges nearly over its centre and the edge of the lower knife nearly on a level with the top of the barred roller. There are two knives which are placed the thickness of the slave apart and are secured to the side pieces of the frame by screw bolts which pass down through them. The other rollers are all plain and are for guiding the slave to the knives. The slaves may be forced through the knives by a driver and lever attached to a crank shaft by a pitman and will force a slave through at every revolution of the crank.

3rd The part for shaving hogs. This is made similar to the one last described for shaving slaves except that the side pieces are placed one and a half inch apart instead of five and that the upper knife instead of being straight is formed semicircularly. Instead of the small cogwheel on the end of the barred roller meshing into a large cog wheel, a crank handle turned may be used where necessary.

4th To joint the slaves two posts of six long and quarters square (one on left) are erected on two of the cross timbers of the frame and within 5 inches of one of the long timbers, at the distance of five feet from end to end with a piece 12 inches wide by five inches in thickness framed across the top. a groove is cut out of the corner of each of the upright posts in which a gate (hereafter described) slides up and down. The gate is made of 2nd timber (about 14 by 5 inches) four feet long and four feet wide, the lower piece of which stands back about one inch from the front edge, in the centre of the gate and standing perpendicular is an upright made of timber 3 by four inches. The knife is made of a piece of steel in the form of an L three angles curved to suit the edge of the slave and secured on front of the

gate, in the downward motion and when the pointing is performed, it rubs against a piece of wood fastened to the long timber of the main frame, the piece of wood is hollowed out to suit the shape of the back of the slave, and on which the slave is placed for pointing, to the lower end of the gate is attached one end of a piston rod the other end of which is attached to a main shaft, having a cog wheel on its end meshing into another cog wheel on the main shaft hereafter to be described.

5th To turn and cover the head. Two head blocks, are erected in the centre of the main frame, on two of the cross pieces thereof, between these head blocks is placed a wheel 10 inches in length, & in diameter having one of its quidgongs extending through one of the head blocks, on which is secured a circular block 10 inches in diameter, on the face of which are placed bars, to secure the head to be turned. The head is secured against the circular block while turning, by a screw passing through a movable head block of the same height as those first mentioned and placed opposite the circular block, a band passes round the above mentioned wheel to the drum below, on the main shaft by which the circular block is turned. The dressing is performed by having two small bats with whist on one end placed at proper distance and turned by straps round the drum below.

6th The part for dressing ends of barrel and cutting wire. A shaft 4 feet or more in length with its quidgong running in head blocks, is placed directly over the main shaft of the machine, and parallel with it; on the end of one of the quidgongs is a wheel, round which a strap going round the drum on the main shaft below to give motion to the shaft, through this shaft near each end and at the distance of two feet from end to end, are four arms, crossing at right angles, each arm projecting 12 inches from the shaft and being 4 inches square, in the centre of each of these is a round or a square hole about one and a half inch diameter into which is placed slide having an iron bar on its end, through each arm is cut a square mortise, parallel with the shaft, and at right angles with the hole in the arm.

into which may be put a wedge or key. The head block at one end of the shaft is hung with a hinge, so as to allow it to be thrown back out of the way in order to admit the barrel on the arms of the shaft.

7th The first gear facing the heading. A wheel about 6 feet in diameter and of one inch thickness, is placed on the end of the main shaft opposite to that where the power is applied, on the face of this wheel is placed a knife, two feet or more in length, the binding from near the outer edge toward the centre. The head to be faced is cramped in a small frame about 3 feet 6 inches long and 10 inches wide by means of a screw operating on a moveable part of the frame; it is then slipped on a pivot in the centre of the wheel and supported by a platform below it, pressed against the knife-wheel while the facing is performed.

8th Cog Wheels. On the end of the quidgones of each of the barrel rollers is a small cog-wheel, directly below these and meshing with them are large cog-wheels. These are on the main shaft of the machine. Another cog-wheel on the main shaft, meshes with the cog-wheel on the crank-shaft working the gate of pointing machine.

9th The draw and shafts. The main shaft is placed about the middle of the frame and parallel with it having its quidgones, running in boxes, on the top of the cross pieces of the frame, near the centre of the shaft is a large chain, around which pass the loops to the chain before described. To this main shaft is applied the drawing power which may be steam, water, animal or any other power.

Operation. The machine being put in motion, the stone to be shaved is placed on the rollers with the end between the barrel and binding rollers and as the motion of the machine is caused forward to the stones, forced through between them and shaved. The stone is next removed to the pointing part laid on the curved piece of timber, or sled and bound by means of the gate brought down upon it which at one or more points it. The loops and heads are forced at the same time. These parts are then put together by hand and the handle formed. It is then taken to the face of the machine.

for dropping the end and cutting the croze, which is done by placing it over the arms of the shaft and driving up the wedges, or pegs, which force out the steel with their points which secure the barrel in its place while doing the work.

All that we claim as our invention and which we wish to secure by letters patent is, the above described machine for making barrels, pails and other cooperage.

The testimony whereof we have hereunto subscribed our names before two witnesses and made oath to the same this ninth day of September 1831.
